N. GRAY BARTLETT, OF KEOKUK, IOWA.

Letters Patent No. 73,284, dated January 14, 1868.

IMPROVEMENT IN INKSTANDS.

The Schedule referred to in these Letters Patent and making part of the same.

TO ALL WHOM IT MAY CONCERN:

Be it known that I, N. GRAY BARTLETT, of Keokuk, Lee county, Iowa, have invented a new and improved Fountain-Inkstand; and I do hereby declare that the following is a full, clear, and exact description thereof, which will enable others skilled in the art to make and use the same, reference being had to the accompanying drawings, forming part of this specification.

My improvements consist in the employment of an overflow-chamber, in connection with a fountain-inkstand, and in the peculiar arrangement of the pen-orifice or fountain-tube.

The overflow-chamber is so disposed in the inkstand that its bottom, or floor, is continuous with the upper margin of the duct leading from the reservoir to the pen-orifice or fountain-tube, so that when any expansion of air confined in the reservoir takes place, the ink thereby displaced will be received in the overflow-chamber, whence, upon contraction of the confined air, it will return through the duct to the reservoir.

The pen-orifice or fountain-tube in my improvement slopes upward at an angle of about forty-five degrees to the perpendicular face of the inkstand. By this arrangement, convenience in use and facility in filling the inkstand are secured, while the perpendicular relation of the orifice to the base tends to exclude dust and dirt. In the accompanying drawings—

Figure 1 is a top view of my improved fountain-inkstand.

Figure 2 is a horizontal section thereof at line xx of fig. 4.

Figure 3 is a vertical section thereof at line yy of fig. 2; and

Figure 4 is a vertical section at line zz , also of fig. 2.

Similar letters of reference indicate corresponding parts.

A is the frame or stand; B, the closed reservoir, hermetically sealed to the vessel b , the floor whereof, at b , is level with that of the duct C. D is the overflow-chamber, having its floor above the level of that of the duct C, as shown in fig. 4, and open to it, as shown in figs. 3 and 4.

The inkstand is filled by placing the plane of its base in a vertical position, and pouring the ink through the pen-orifice E, fig. 3. The opening of D into C is level with, and it is desirable that it should extend the entire width of the floor of D, which slopes slightly upwards from C, so that upon contraction of the air in B, any ink which may have flowed into D will descend into C, and thence re-enter the reservoir. E is the fountain-tube, sloping at about forty-five degrees to the perpendicular face of the inkstand.

The defect in ordinary fountain-inkstands, which this invention is intended to overcome, is their liability to overflow, from the variations of temperature. This fact may be exemplified as follows: Suppose the ink to occupy but a portion of the reservoir, at the ordinary day-temperature, then, when the inkstand is exposed to a colder atmosphere, a condition generally fulfilled at night, and more especially during the winter season, the air in the space above the ink will contract, and the pressure of the atmosphere upon the ink in the duct will cause it to re-enter the reservoir. This recession of the ink in the duct will permit the access of so much air to the confined space as may be required to establish an equilibrium between the interior and exterior pressure. On the succeeding day, when the temperature is higher, the air in the reservoir will expand, and having no means of egress, will displace the ink, and cause it to flow from the fountain-tube over the exterior of the inkstand; and this overflow will recur at every considerable variation of temperature.

In my improvement, this overflow of ink is received and retained in the chamber D, which is so arranged, in connection with the duct C, that upon contraction of the air in the reservoir, this volume of ink will re-enter the reservoir instead of an equal increment of air. The area of the reservoir bears such relation to the capacity of the overflow-chamber as to render the overflow of the latter impossible from any variations of temperature to which an inkstand is exposed.

Having thus described my invention, what I claim as new, and desire to secure by Letters Patent, is—

The overflow-chamber D, in combination with a fountain-inkstand, substantially as herein shown and described.

N. GRAY BARTLETT.
